UNITED STATES PATENT OFFICE.

ALFRED COOKE, OF HARLESDEN, ENGLAND, ASSIGNOR TO PEEK FREAN AND COMPANY, LIMITED, OF LONDON, ENGLAND, A CORPORATION OF GREAT BRITAIN AND IRELAND.

DESIGN FOR A BISCUIT OR LIKE ARTICLE.

45,523.

Specification for Design.

Patented Mar. 31, 1914.

Application filed December 8, 1913. Serial No. 805,470. Term of patent 14 years.

To all whom it may concern:

Be it known that I, ALFRED COOKE, a subject of the King of Great Britain, residing at Harlesden, in the county of Middlesex, England, have invented a new, original, and ornamental Design for a Biscuit or like Article, of which the following is a specification, reference being had to the accompanying drawing, forming a part thereof.

The figure is a plan view of a biscuit showing my new design.

The design consists of a representation of a portion of the North and South American continents with an ornamental scroll across between them. On the scroll is the word "Panama." Above the scroll is the letter P and below the scroll is the letter F. The whole is contained within a circular border.

I claim:

The ornamental design for biscuit or like article as shown and described.

ALFRED COOKE.
